MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,339,820.

Specification of Letters Patent. Patented May 11, 1920.

Application filed July 15, 1919. Serial No. 310,933.

To all whom it may concern:

Be it known that I, MONROE GUETT, a citizen of the United States, residing at Hartford, in the county of Hartford and 5 State of Connecticut, have invented certain new and useful Improvements in Electric Switches, of which the following is a specification.

This invention relates to electric switches. 10 I am not restricted to the incorporation of the invention in a switch of any particular type, although the same is of especial utility, however, when employed in conjunction with a switch, the switching or circuit-controlling member of which has a back and forth movement, generally oscillatory, about an axis. A switching or circuit-controlling member of this nature has at least 15 two positions, one, the "off" and the other, "on." When the switching or circuit-controlling member is in the "on" position, it coöperates with contacts which press against the free portion or end of the switching or circuit-controlling member. 20 Heretofore, the force ordinarily employed primarily by manually-operable means, is not efficiently applied. I overcome this 25 drawback in a satisfactory manner and this I might observe at this point is probably the primary motive I have in view.

In the drawings accompanying and forming part of the present specification, I have shown somewhat in detail, one of the several forms of embodiment of the invention, 30 which to enable those skilled in the art to practice the same, will be set forth in the following description. As may be inferred I am not restricted to this particular disclosure. I may in fact depart therefrom 35 in several particulars within the scope of the invention defined by the claims following said description. Referring to said drawings:—

Figure 1 is a top plan view of the 40 switch, with the switching member in the "off" relation.

Fig. 2 is a section on the line 2—2 of Fig. 1, looking in the direction of the arrows.

45 Figs. 3 and 4 are sectional details of the switching mechanism, hereinafter more particularly described and showing the switching member in the "off" and "on" positions respectively, the scale being somewhat 50 larger than that of Figs. 1 and 2.

Like characters refer to like parts throughout the several views.

The different parts of the switch can be supported in any convenient manner. For this purpose I have shown a body as 2, 60 which will usually be made from insulating material or some composition as common in the art. The switching or circuit-controlling member shown is denoted in a general way by 3. It is practically of inverted U or yoke form, being pivotally mounted as at 4 within an aperture in the supporting body 2.

The actuator for the switching member 3, selected for illustration, is denoted in a 70 general way by 5 and it is provided at its ends with insulating knobs or buttons 7 and 8 generally molded onto the bent terminals of the metallic body. The body 6 between its ends, is furnished with pendant studs as 75 9 and 10 disposed in channels 11 and 12 in the upper side of the body 2, the end walls of the respective channels or grooves acting to limit opposite longitudinal movements of the actuator 5. As shown the center or axis 80 of motion of the switching member 3 is situated below the path of movement of the actuator body 6, the legs or branches of the switching member straddling the actuator body. 85

There is disposed between the switching member and the actuator, a pin, which desirably has as shown a sliding connection with one of the parts with which it coöperates and a pivotal connection with the other, 90 a pin of this character being denoted by 13. This pin is shown as having at its lower or inner end a fork 14 in straddling engagement with the cross bar 15, of the actuator body 6. The cross bar separates the two 95 longitudinal duplicate slots 16 and 17 in said actuator body. The upper or outer end of the pin 13 as shown, has a sliding and free fit in the elongated slot 18 in the cross bar of the switching member. Around the pin 13 is shown a coiled-spring 19 bearing at its lower end against the fork or foot 14 and at its upper or outer end against the cross bar or transverse portion of the switching member 3. 100

The point of connection between the actuator 6 and the pin 13 is alternately moved across a dead center line. In this case the dead center line intersects the axis of movement of the switching member and also 110

passes through the center of that part of the pin 13 against which the upper end of the spring 19 bears or practically through the center of the slot 18.

5. In Fig. 4 the switching member 3 is shown as being in the "on" relation, it being between the free portions of the yieldable or springy terminals 20 of contacts as 21 fastened to the body or base and to which terminals wires (not shown) are electrically and mechanically connected. In this particular view the actuator 5 through the manipulation of the button 8 (Figs. 1 and 2) is supposed to have been pushed or pulled 10 practically to the limit of its movement toward the right. This movement of the actuator caused the center of connection between the fork 14 and the bar 15 to move across the dead center line to which I have 15 referred and naturally resulted in the upward movement relatively of the pin 13 and the consequent compression of the spring 19. I have assumed the spring to be under virtually maximum compression in said 20 Fig. 4, the actuator as having completed its stroke through manual operation, and the switching member as ready to commence its movement. When it does move it follows the direction of the arrow in said Fig. 4, 25 the compression spring causing the snap movement of the switching member to the "off" position.

In Fig. 3 the actuator 5 is supposed to have completed practically its movement toward the left. This particular movement of course resulted in the conditioning of the spring, by compression of course in the present case, so that when the center of connection between the actuator 5 and the pin 13 30 has practically crossed the dead center line the switching member will be free to be shifted by the compression spring 19, in the direction of the arrow in Fig. 3. The motion of the actuator is of course necessary to 35 secure the conditioning of the spring, the latter by reaction on effecting the snap movement of the switching member.

It requires less force naturally to start the switching member from the "off" to the 40 "on" than from the "on" to the "off" positions. In the movement from "off" to "on" the motion of the cross bar 15 by or past the dead center line of the switch, is less than the motion of the cross bar by or past said 45 dead center line, when the switching member is moved from the "on" toward the "off" position. As it might be otherwise stated the distance traveled by the center of connection between the bar 15 and the pin 13, is 50 greater at one side of the dead center line than at the other side, being greater at what is shown as the right side of said line than at the left side. I obtain advantages 55 by this, the principal of them being that I 60 secure the necessary amount of torque to 65

properly overcome the resistance on what is shown as being the left side of said dead center line, at which time the movement of the switching member is retarded by the friction of the contacts.

70

What I claim is:—

1. A switch comprising an actuator mounted for back and forth movement, an oscillatory switching member, a pin between the actuator and the switching member, having a pivotal connection with one and an operative connection with the other, a spring between the switching member and the pin, the actuator on each movement thereof being adapted to condition the spring to snap the switching member, and contacts engageable by the switching member, the range of movement of the point of connection between the actuator and said pin being greater on one side of the dead center line than on the other side of said line.

2. A switch comprising an actuator mounted for back and forth movement, an oscillatory switching member, a pin between the actuator and the switching member, having a pivotal connection with one and an operative connection with the other, a spring between the switching member and the pin, the actuator on each movement thereof being adapted to condition the spring to snap the switching member between the "on" and "off" positions thereof, and contacts engageable by the switching member, the range of movement of the point of connection between the actuator and said pin being greater on that side of said dead center line at which the contacts are located than on the other side of said line.

3. A switch comprising an actuator mounted for back and forth movements and an oscillatory switching member, one of the parts having a bar, a pin having a fork in straddling engagement with the bar and operatively associated with the switching member, the range of movement of the point of connection between the actuator and the pin, being greater on that side of the dead center line of the switch, at which the contacts are located, than on the other side of said line and a spring interposed between the switching member and the actuator.

4. A switch comprising an actuator mounted for back and forth movement, an oscillatory switching member, a pin between the actuator and the switching member, the pin having a fork and the actuator having a cross bar to be straddled by the fork, the switching member having a slot through which the pin extends, a spring around the pin and bearing against the fork and also against the switching member, the actuator on each movement thereof being adapted to condition the spring to snap the switching member across the dead center line of

the switching mechanism, and contacts engageable by the switching member, the range of movement of the point of connection between the actuator and said pin being greater on that side of said dead center line, at which said contacts are located, than on the other side of said line.

5. A switch comprising an actuator mounted for back and forth movement, an oscillatory switching member, pin and spring means between the switching member and the actuator, the pin being connected with the actuator, and contacts engageable by the switching member when in the "on" 10 relation, the actuator being adapted on each 15

of its movements to condition the spring means to impart a snap to the switching member to carry the same across the dead center line thereof, the point of connection between the pin and the actuator having a greater travel on that side of the line at which the contacts are located than on the opposite side of said line.

In testimony whereof I affix my signature in the presence of two witnesses.

MONROE GUETT.
